UNITED STATES PATENT OFFICE.

WALTER L. KEEFER, OF FITCHBURG, MASSACHUSETTS.

MICROMETER.

1,100,573.

Specification of Letters Patent. Patented June 16, 1914.
Application filed June 23, 1913. Serial No. 775,425.

To all whom it may concern:

Be it known that I, WALTER L. KEEFER, a citizen of the United States, residing at Fitchburg, in the county of Worcester and State of Massachusetts, have invented certain new and useful Improvements in Micrometers; and I do declare the following to be a full, clear, and exact description of the invention, such as will enable others skilled in the art to which it appertains to make and use the same.

This invention relates to measuring instruments, and more especially to gages; and the object of the same is to produce an improved micrometer wherein the movable jaw is constantly pressed with gentle force toward the fixed jaw although it can be retracted instantly by hand, and wherein certain advantageous features of construction are embodied, as set forth in the following specification and claims, and as shown in the drawings wherein—

Figure 1 is a front elevation of this instrument complete, and Fig. 2 is a similar view with the dial, crystal, and face plate of the casing removed. Fig. 3 is a side elevation of the instrument, and Fig. 4 is a plan view thereof. Fig. 5 is a vertical section through the casing, taken on the line 5—5 of Fig. 1. Figs. 6 and 7 are elevations of the plunger from different view points. Figs. 8 and 9 are side elevations of different forms of points or jaws. Fig. 10 is a detached elevation of the dial.

The frame of this improved instrument comprises a tubular barrel 1 cut away at one point in its side as shown at 2, and a yoke 3 whose upper end is connected with the lower end of said barrel, whose body curves to one side, and whose lower end carries a socket 4 in which is mounted what might be called the fixed jaw or lower point. The barrel carries a casing 5 of cylindrical contour and projecting away from the same on a line preferably at right angles to that occupied by the yoke 3, and the back of this casing is closed while its front carries a ring-shaped dial 6 having graduation marks over which moves the tip of an index yet to be described, the dial being covered by a crystal 7 which is held in place within the casing by a ring 8 or other suitable means. The lower point is carried by said socket 4, which is internally threaded as at 10 to receive a screw 11 preferably having extremely fine threads so that the accuracy of this instrument may be

maintained by setting this screw correctly. When the screw is run up within the threaded socket the tip of the screw projects above the same and itself forms the lower point or fixed jaw. Or, if desired, the screw may be run downward in the socket whose upper end is forked and the fork arms perforated as at 12, and in that case the pivot pin of a small roller 13 may be mounted in these perforations and the roller itself will constitute the lower point or fixed jaw for a purpose yet to appear. The movable jaw or upper point is carried at the lower end of a plunger 15, preferably cylindrical, which moves through the tubular barrel 1 and is provided with a longitudinal groove 16 engaged by the tip of a screw or pin 17 in the side of the barrel so as to prevent the plunger from rotating therein. One side of this plunger is provided with graduations as shown at 18, and its upper end has a kn 19. Its lower end is pierced with a transverse perforation 20 through which may pass a pin by means of which the upper point is detachably connected with said end. Such point consists of a fixed member 21 as shown in Fig. 8 which coacts with the screw 11 when the latter is run up in the threaded socket, or a socket member 22 forked at its lower end and carrying a roller 23 journaled between the fork arms on a line parallel with the axis of the roller 13, this member co-acting with the roller member when the latter is employed for the lower jaw.

I might say at this point that one of the features of the present micrometer is that it may be used on a rotating element, such as a shaft, without checking the rotation thereof. This is done by means of the jaws which carry the rollers whose axes stand in a plane at right angles to that of the yoke 3 as shown; but at other times it is possible to use the stationary jaws or jaw faces 21 and 11, the latter being the upper end of the screw.

One side of the plunger 15 is provided with a rack 15' consisting of extremely fine teeth, preferably disposed at a slight angle to the horizontal, and this rack is so located that it will project through the cut-away portion 2 of the barrel 1 and into the interior of the casing 5. Within the latter, in a suitable framework consisting of two plates 30 properly spaced, is mounted a train of gears having extremely fine teeth so that they will mesh with each other and

with the rack 15' on the plunger; and, while I do not wish to be limited to the number of these gears or their teeth or disposition, I will describe what is illustrated in the drawing as typical of one means for carrying out my invention. The rack meshes with an idle gear 31 and the latter with a small pinion 32 which is designed to revolve twice every time the spindle is moved one inch. Fast on the shaft of this pinion is a gear 33 meshing with a pinion 34 having one-fifth of its number of teeth, so that when the gear 33 revolves once the pinion 34 will revolve five times. It follows that as the plunger is moved one inch, the pinion 34 is caused to make ten revolutions. Fast on the shaft of this pinion is a hand or index 35 which moves over the graduations on the dial 6, and as one revolution of the hand indicates one-tenth of an inch the graduations on this dial may be very fine so that hundredths, thousandths, and even ten-thousandths of an inch can be ascertained without the use of glasses. On the other side of the index fingers 31 I preferably dispose within the frame plates 30 a gear 36 also meshing with the pinion 34, and itself driven by a fine coiled spring 37. The tendency of this spring is to rotate the spring gear 36 in such direction that the train of gears will normally depress the plunger 15, and I would make the strength of the spring 37 barely sufficient to perform this function so that the operator need but lightly grasp the knob 19 and lift the plunger to open the jaws wider than the article being measured, and when he removes his fingers the uncoiling of the spring 37 restores the parts to their working position as will be clear.

Another feature of my invention is a collar 40 which surrounds plunger 15 above the upper end of the barrel 1, and is adjustably mounted thereon as by being split at one side and turned outward into ears 41, which latter may be clamped by a set screw 42 passing through them. The graduations 18 (preferably indicating one-tenths of an inch) may be read beneath this collar and above the upper end of the barrel as seen in Fig. 1, but the use of this collar is as follows: Assuming that the operator is measuring a number of articles which are approximately one inch in diameter or size, he may set the collar to permit the instrument to measure a little under an inch, and then each time it is brought into use he grasps the knob 19 and draws the plunger 15 upward only sufficiently to permit the jaws to pass over the object, after which he releases the knob and the spring throws the jaws into contact therewith. Then, glancing at the dial, he notes the size indicated thereon, after which he can pull the micrometer off the article and the spring

depresses the plunger until the collar 40 strikes the upper end of the barrel at a point when the distance between the jaws is something less than an inch but not much less. Thereafter when he comes to measure the next object he has not so far to raise the barrel as if the latter were permitted to descend to its lowest extremity under the influence of the spring. In any event it would not take much time to do this, because he can grasp the knob 19 and draw the plunger rapidly upward, rather than unscrewing it by the laborious process common to micrometers now on the market; but it is not necessary to do even this when the collar 40 is employed, as he has but a little way to lift the plunger for the reason just stated.

The casing is dust proof and moisture proof, and while I have shewn a small train of gears and given the preferred proportion of teeth, it will be clear that any suitable train of gears might be employed so that the movement of the plunger 15 will be registered on the dial. The size and materials of parts are not essential, and the uses of instruments of this kind are too well known to need elaboration in this specification.

What is claimed as new is:

1. In a micrometer, the combination with a frame including a tubular barrel, a yoke, and a fixed point carried by said yoke in line with said barrel, a plunger movable through the latter and having graduations, a movable point at the lower end of the plunger and means for pressing the plunger normally toward the fixed point; of a collar removably and adjustably mounted on the stem of the plunger above said barrel and adapted to be set with respect to said graduations, for the purpose set forth.

2. In a micrometer, the combination with a frame having at its lower end a yoke terminating in a threaded socket and at its upper end a barrel in line with said socket, the wall of the socket being forked and pierced with perforations through the fork-arms, and a lower point including a roller whose trunnions are removably engaged with said perforations; of a plunger movable through said barrel and having a transverse perforation in its lower end, and an upper point removably engaged with said perforation.

3. In a micrometer, the combination with a frame having a tubular barrel, a yoke, and a fixed jaw in line with said barrel, and a roller mounted in said jaw on an axis at right angles to said yoke; of a plunger movable through said barrel and having a socket member at its inner end which member is forked at its inner extremity, and a roller journaled between the fork arms, for the purpose set forth.

4. In a micrometer, the combination with

- a frame including a barrel cut away at one side, a yoke projecting from the lower end of said barrel, and a fixed jaw carried by the lower end of the yoke; of a plunger slidably mounted through said barrel and having a rack projecting through said cut-away portion, the body of the plunger being longitudinally grooved and its lower end carrying a movable jaw coacting with said fixed jaw,
- 5 10 a pin through the side of the barrel engaging said groove, and indicating mechanism including a gear projecting through said cut-away portion of the barrel into engagement with said rack.
- 15 5. In a micrometer, the combination with a frame including a tubular barrel cut away at one side, a pin in the barrel, a casing on the frame, a dial on the casing, a yoke projecting outwardly from the lower end of said barrel, and a fixed jaw carried by said yoke;
- 20 of a round plunger slidably mounted through said barrel and having a groove along one side engaging said pin and a rack opposite said cut-away portion, the body of the plunger being inscribed with a scale, a 25 collar mounted on the plunger above said barrel and adjustably along said scale, a movable jaw at the lower end of the plunger, indicating mechanism carried by said casing over the dial and connected through said 30 cut-away portion with said rack, and yielding means for moving the plunger toward the fixed jaw.
- In testimony whereof I have hereunto set my hand in presence of two subscribing witnesses.
